LIQUID TREATING APPARATUS

Joseph A. Truitt, West Chester, Pa., assignor to American Viscose Corporation, Philadelphia, Pa., a corporation of Delaware

Application October 29, 1952, Serial No. 317,445

6 Claims. (Cl. 68—19)

The present invention relates to the manufacture and production of synthetic filamentary materials and more particularly to novel apparatus for liquid treating such materials, yarns and the like in a uniform and controllable manner.

In the manufacture of various types of filamentary materials and yarns, it is ordinarily customary to process a plurality of individual filaments simultaneously in the form of a bundle such as a yarn or tow. In so doing, however, it has oftentimes been found difficult to properly treat and/or process the entire surface area of each of the individual filaments properly and uniformly. Moreover, although various procedures and apparatus for providing for uniform treatment of the continuously advancing filamentary material or the like have been devised and employed in the past, particular difficulty has been experienced in lacing such apparatus in a ready and convenient manner.

It is a principal object of the present invention to provide novel apparatus for liquid treating filamentary materials, yarns and the like in a thorough and uniform manner.

It is a further object of the present invention to provide novel and improved liquid treating apparatus through which the filamentary material to be treated may be readily and conveniently laced.

Other objects and advantages of the present invention will be apparent from the following description.

In the drawing which is illustrative of the present invention,

Figure 1 is a side elevational view of a preferred embodiment of the present invention with a portion thereof shown in section;

Figure 2 is an end view of the embodiment shown in Figure 1 with part of the trough broken away;

Figure 3 is an enlarged view in perspective of a detail of the apparatus shown in Figure 2; and

Figure 4 is a diagrammatic view illustrating a step in the simplified lacing procedure which forms a part of the present invention.

In general, the improved filamentary material liquid treating apparatus includes an elongated conduit means for directing a treating liquid through the conduit in a given direction and at a predetermined rate, and means for continuously passing a bundle of filamentary strands through the conduit in the same direction and substantially at the same rate. It has been found that the liquid treating process may be controlled with improved accuracy and uniformity in such a manner.

The hereinafter described apparatus has been found particularly useful where, as shown in the drawings, the continuously advancing yarn or the like is withdrawn from a conventional thread-advancing device, is treated with a suitable yarn lubricant or finish, and is returned to the thread-advancing device. In this way, as will be more apparent hereinafter, the yarn may be treated, dried or processed in any suitable manner as it progresses along the periphery of the thread-advancing device. It is to be

2

understood, however, that the apparatus of the present invention could also be employed in any other conventional liquid treating operation without departing from the spirit or scope of the present invention.

A preferred structural embodiment of the present invention is shown in Figures 1 through 3 of the drawing. As illustrated therein, the improved liquid treating apparatus which is generally designated in the drawing by the reference numeral 3 is preferably positioned beneath a suitable portion of the filamentary material processing apparatus so that the filamentary bundle 5 may be conveniently and directly conducted thereto. Accordingly, the liquid treating tank or the like 6 is shown in the drawing positioned beneath the thread-advancing device which is generally designated by the reference numeral 4 and which preferably comprises the drying drum 7 and the roll or the like 7a canted thereto.

The liquid treating conduit or the like 8 which is preferably L-shaped as shown is mounted in any convenient manner on the bracket members or the like 9 and 10 which are secured to the bottom of the treating tank 6 in any suitable manner such as by the welding shown at 11 and extend upwardly therefrom. The upright extremity 8a of the liquid treating conduit 8 is preferably externally threaded as at 12 to receive the internal threads of the sleeve member or the like 13 which as will be explained more fully hereinafter permits control and regulation of the fluid flow through the conduit. As will also be explained more fully hereinafter, the treating liquid is preferably delivered to the conduit 8 from any suitable source such as that shown diagrammatically at 14 through the conduit or the like 15.

It is to be understood that although not shown in the drawing a plurality of sleeves which vary in length one from another could be also used to provide an increased range of control of the fluid rate through the conduit 8 without departing from the spirit or scope of the present invention.

As best shown in Figure 3 of the drawing a substantial portion of the upper half of the conduit 8 preferably adjacent its other extremity is cut away as at 16. The complementary half-round tubular casing, cover, or the like 17 which is adapted to be clamped into position on the cutaway portion of the conduit by any suitable conventional clamping members such as the resilient clip members 18 which cooperate with the notched portions 18a of the casing 17 is preferably notched as at 19 and 20 to facilitate the delivery of the continuously advancing tow or yarn 5 into conduit 8 and its removal therefrom. The guide support members or the like 21 and 22 are preferably located as shown at opposite extremities of the casing 17 so as to aid in centering the yarn within the conduit 8 when the casing is properly positioned on its cut away portion. More specifically each of the guide support members is preferably recessed as shown to receive the guide inserts 23 which are formed from porcelain, glass, or any other suitable wear resistant material and which as will be more apparent hereinafter, are adapted to engage the continuously advancing material. The resilient clip members 24 which are integral with the opposite extremities of each of the guide support members 21 and 22 and which extend through the notches 25 in the casing 17 and upwardly about its outer periphery as shown normally maintain the guide members in their proper position adjacent the opposite extremities of the casing.

As is best shown in Figure 3 of the drawing when the half-round tubular casing or cover 17 is properly positioned and secured to the conduit 8 and the adjacent extremities of the casing and the enclosed portion of the conduit abut one another, the cutaway portion of the conduit

preferably extends beyond the opposite extremity of the casing. In this way, though not shown on the drawing, any conventional means for extending or varying the length of the casing could be employed to control the immersion path of the continuously advancing yarn in the conduit.

It is to be understood that, although the conduit 8 is preferably cut away adjacent an extremity thereof as shown, a central portion of the conduit could instead be cut away to receive the casing 17 without departing from the spirit or scope of the present invention.

The overflow pipe or the like 26 preferably extends as shown in Figure 1 of the drawing upwardly through the aperture 27 and the conventional fluid seal 28 positioned on the bottom of the treating tank 6. The upper extremity of the overflow pipe is preferably externally threaded as at 29 to receive and cooperate with the interior threads of the adjusting sleeve member 30 positioned thereon. Though not shown on the drawing, the lower extremity of the overflow pipe 26 is preferably connected by any suitable means to a conventional fluid return system or the like.

As shown diagrammatically in Figures 1 and 2 of the drawing the conventional adjustable yarn stripping device 31 is preferably positioned so as to contact the continuously advancing yarn or tow 5 as it proceeds between the discharge extremity of the liquid treating conduit 8 and the processing apparatus 4. In this way, as will be more apparent hereinafter, the yarn stripping device 31 serves a dual purpose in that it effectively removes excess treating liquid on the continuously advancing yarn and simultaneously reduces the yarn tension during the liquid treating operation so as to facilitate the separation of the individual filaments of the tow in the conduit 8.

In operation, the continuously advancing yarn or tow 5 which is to be processed in accordance with the improved liquid treating apparatus of the present invention is conducted, as is best shown in Figure 1 of the drawing, from the strand advancing and drying drum combination 7, 7a through the treating conduit or the like 8 and returned by way of the stripper device 31 to the processing apparatus. As shown in Figure 4 of the drawing in order to lace the apparatus, the casing 17 is temporarily removed from the cut away portion of the conduit 8 and a loop of the yarn 5 which is relatively resilient and/or pliable is preferably drawn downwardly from the thread-advancing and drier combination 7, 7a. The closed end of the loop is then passed through the notches 19 and 20 in the casing 17, successively through the recesses in the guide inserts 23 in the guide members 21 and 22, between the bars of the stripping device 31, and back to the thread-advancing device 4. The casing 17 is then again secured to the cut away portion of the treating conduit 8 by means of the conventional clamping members 18. The position of the sleeve 30 on the upper extremity of the overflow pipe or conduit 26 is then adjusted to properly control the level of the treating liquid in the tank 6. Similarly the position of the sleeve 13 on the upper extremity 8a of the conduit 8 is then adjusted to control the velocity of the fluid therethrough and to maintain it at substantially the same velocity as the rate at which the continuously advancing yarn or tow travels through the conduit 8. When the rates of the flow of the treating liquid and of the yarn through the conduit 8 are properly adjusted in this way, and when the continuously advancing material is properly threaded through the stripper device 31 to reduce the yarn tension during the liquid treating operation, it has been found that the individual filaments of the yarn or tow then tend to separate one from another as best illustrated in Figure 3 as they proceed through the conduit 8.

While preferred embodiments of the invention have been disclosed, the description is intended to be illustrative only and it is to be understood that changes and variations may be made without departing from the spirit

and scope of the invention as defined by the appended claims.

I claim:

1. Liquid treating apparatus for a continuously advancing filamentary material comprising an elongated tubular conduit, a substantial lateral portion of the conduit being cut away, means for continuously supplying the conduit with controlled amounts of the treating liquid, an elongate member of arcuate cross section, means for releasably clamping the member to the conduit where it is cut away to enclose the cut away portion of the conduit, and means including guide members positioned at opposite extremities of said elongate member and notches in the curvilinear end edges thereof for conducting the filamentary material into and out of the enclosed cut away portion of the conduit.

2. Liquid treating apparatus for continuously advancing filamentary material comprising an open trough-like container, an elongated tubular conduit which is generally positioned along the length thereof, a substantial longitudinal portion of the tubular conduit being cut away adjacent one extremity, means for supplying the conduit with controlled amounts of a treating liquid, means for controlling the level of the treating liquid in the trough-like container, an elongate member of arcuate cross section, means for releasably clamping the member to the conduit where it is cut away to enclose the cut away portion of the conduit, and means for conducting a filamentary material, into, through, and out of the enclosed cut away portion of the conduit.

3. Liquid treating apparatus for a continuously advancing filamentary material comprising an open trough-like container, an elongated tubular conduit which is generally positioned along the length thereof, a substantial portion of the tubular conduit being cut away adjacent one extremity, means for continuously supplying the conduit with controlled amounts of a treating liquid, means for controlling the level of the treating liquid in the trough-like container, an elongate member of arcuate cross section, clamping means for securing said member to the conduit to enclose its cut away portion, and means including guide members positioned at opposite extremities of the said elongate member and notches in the curvilinear end edges thereof for conducting the filamentary material into and out of the enclosed cut away portion of the conduit.

4. Liquid treating apparatus for a continuously advancing filamentary material comprising an open trough-like container, an elongated tubular conduit which is generally positioned along the length thereof, a substantial longitudinal portion of the tubular conduit being cut away adjacent one extremity, means for continuously supplying the conduit with controlled amounts of a treating liquid, an overflow pipe extending upwardly through the bottom of the container, an adjustable sleeve member positioned on the upper extremity of the overflow pipe, an elongate member of arcuate cross section, means for releasably clamping the member to the conduit where it is cut away to enclose the cut away portion of the conduit, and means for conducting the filamentary material into and out of the enclosed cut away portion of the conduit.

5. Liquid treating apparatus for a continuously advancing filamentary material comprising an open trough-like container, an elongated tubular conduit which, except for one extremity that extends upwardly out of the container, is generally positioned along the length thereof, substantially one half of the longitudinal portion of the tubular conduit adjacent its opposite extremity being cut away, an adjustable sleeve member positioned on the first-mentioned extremity of the conduit, means for continuously supplying the first-mentioned extremity of the conduit with a treating liquid, an overflow pipe extending upwardly through the bottom of the container,

an adjustable sleeve member positioned on the upper extremity of the overflow pipe, an elongate member of arcuate cross section, clamping means for releasably securing said elongate member to the conduit to enclose its cutaway portion, and means including guide members positioned at opposite extremities of said elongate member and notches in the curvilinear end edges thereof for conducting the filamentary material into and out of the enclosed cut away portion of the conduit.

6. Apparatus for processing a continuously advancing filamentary material comprising thread-advancing means, an elongated tubular conduit, a substantial lateral portion of the conduit being cut away, means for continuously supplying the conduit with controlled amounts of a treating liquid, means for enclosing the cut away portion of the conduit, means for conducting the filamentary material from the thread-advancing means through an enclosed cut away portion of the conduit and back to the thread-advancing means, and means disposed along the path of the filamentary material from the con- 10 15 20

duit back to the thread-advancing means for applying tension to the filamentary material and for stripping excess liquid therefrom.
